ERNESTO ANSALDI, OF LEGHORN, ITALY.

Letters Patent No. 70,774, dated November 12, 1867; patented in Italy, September 10, 1866.

IMPROVEMENT IN STEAM ENGINES.

The Schedule referred to in these Letters Patent and making part of the same.

TO ALL WHOM IT MAY CONCERN:

Be it known that I, ERNESTO ANSALDI, of Leghorn, in the Kingdom of Italy, have invented certain Improvements in Steam Engines; and I do hereby declare that the following is a full and exact description thereof, reference being had to the accompanying drawings, and to the letters of reference marked thereon.

These improvements in steam engines consist in a novel arrangement of the same, with the object of doing away with what in steam engines are called the dead-points, thereby dispensing with the use of a fly-wheel, and obtaining an important saving in power and a more simple arrangement of the engine; and they consist in making use of two cylinders, set either concentrically to each other or placed side by side, and suitably connected together, the whole being arranged and acting in the manner as will be set forth in this description, and illustrated by the annexed drawings, in which latter the figs. 1, 2, 3, 4, 5, 6, and 7 show various views of an engine, the two cylinders of which are set concentrically to each other, the figs. 8 and 9 showing a modification of this arrangement, whereas the remainder of the figures illustrates the application of the invention to an engine having its two cylinders situated side by side, and suitably connected together.

Figure 1 shows a side elevation, and

Figure 2 a plan view of an engine, the two cylinders of which are set concentrically, viz, the smaller one within the large cylinder.

Figure 3 shows a longitudinal vertical, and

Figure 4 a horizontal sectional view of the same; taken over the axis of the two cylinders.

Figures 5, 6, and 7 show transverse vertical sectional views over the lines X¹ X¹, X² X², and X³ X³ of fig. 2.

Figure 8 shows a transverse vertical sectional view of a modification in the situation of the valve-chests and valves, and

Figure 9 an outside view of this modification, with the chests and valves removed, in order to show the position of the steam-ports and passages.

Figure 10 represents a longitudinal sectional view of the cylinders of an engine constructed according to my improved principle, with the two cylinders situated side by side; the

Figures 11, 12, and 13 showing sectional views of various positions of the valves and cranks.

In all these figures the same letters of reference relate to corresponding parts.

The principle on which my improved steam engines are based is to make only the larger one of the two cylinders really use up the steam, whereas the smaller one serves more particularly for part of the steam to pass through, and by reacting at the required moments on the piston of this smaller cylinder, make the piston of the large cylinder overcome its dead-points, for which purpose the crank of the small piston is situated at right angles with those of the large one, viz, in such manner that whenever the crank or cranks of this latter piston nearly reach their dead-points, the crank of the small piston is about exerting its maximum effect, by which means these cranks mutually cause each other to overcome their dead-points, thereby allowing of doing away with the fly-wheel hitherto employed for this purpose, in consequence of which my improved steam engines are particularly valuable for marine purposes.

The general arrangement of my improved engine, whether its cylinders are situated concentrically or set side by side, does not differ materially from that of ordinary steam engines; the same is provided with the required eccentrics and the necessary arrangements for giving and reversing motion, and other well-known parts.

I will describe first the arrangement and manner of working of the engine in which the cylinders are set concentrically to each other, as shown in the figs. 1 to 9, inclusive, for a horizontal engine.

The small cylinder G is situated concentrically within the large one B, this latter fixed on a suitable platform or base, A. C, D, and D¹ are three steam-chests, in which are situated and work their respective slide-valves y³, y², and y¹. I wish to observe here that other descriptions of valves might be made use of. The chests D¹ and D are connected by a pipe, H¹, whilst another pipe, H, connects the chest C with the inside of the valve y². G¹ is the piston of the inner cylinder, and Z the annular piston of the outer one, the ends of which cylinders are closed by suitable lids and stuffing-boxes, through which work the rods V² for the outer, and the one, T², for the inner piston. I is an arm fixed to the part K, this latter gliding in the guides L L. The arm I serves for moving the shafts 1 and 2 of the valves y³ and y². M is a rod connected to the part K, and supported by

the standard O, which rod takes hold of the shaft or arbor A³, on which is fixed an elliptic eccentric, N, working between two friction-rollers, P, carried by the rod M. This eccentric N consequently drives the parts P P, M, K, I, and thereby imparts the required forward and backward motion to the valves y³ and y², causing them to stop for the required length of time towards the middle of their stroke. Q Q are two pairs of standards, to the top of which are fixed the guides R and R¹, between which glides the curved cross-head S, to which are fixed the shafts V² V² of the piston Z, and the connecting-rods V¹ V¹, actuating the cranks V V, fixed on the main arbor A³. T³ is a forked rod connecting the shaft T² of the inner piston G¹ with a crank, U, connected with those V V, and set at right angle with these latter. This shaft T² works in a guide or bracket, T¹. A¹ are plumb blocks for the main and crank arbors. The valve y¹, constructed on the ordinary principle, receives motion by means of the shaft D², connected by the rod D³ to a circular eccentric, D⁴, fixed on the main arbor A³. This shaft D² glides in a guide-rest, D⁵.

The mode of working of this arrangement is as follows: The steam from the boiler enters by the pipe x into the chest D¹, and is allowed by the tube H¹ to reach the chest D, the valve y² of which distributes the steam into the inner cylinder by means of the channels or steam-ways 3 and 4, provided in the covers of the cylinders. The third chest C receives the steam by the tube H, which steam, however, does not proceed directly from the boiler, but is the superfluous steam of the inner cylinder, and passes through the hollow part of the valve y², as shown in fig. 5; this taking place when the said valve puts the tube H in communication, alternately, with one or the other of the channels 3 and 4. This steam introduced in the chest C, enters into the outer cylinder by the steam-ways 7 and 8, according to which of these latter is open at the time. Supposing now the engine to be at its dead-point, as shown in the drawing, the steam entering by the pipe x fills both chests D¹ and D. At this moment the ways leading into the outer cylinder are kept shut by the valve y¹, which latter is about to open the way 6, whilst in the chest D the valve y² having already opened the way 4, the steam enters thereby, and thus carries down the piston of the inner cylinder, the crank of which being situated at right angles with those of the outer cylinder, carries these latter cranks beyond their dead-point, accompanying them through an angle of about forty-five degrees, and when arrived at about thirty degrees the valve y¹ opens the way 6, and thereby allows the steam to enter the outer cylinder, the piston Z of which has already begun its stroke, which it will thus complete.

Attention is now to be called to the working of the steam on the piston of the inner cylinder, in consequence of the arrangement of the valves y² and y³. Immediately after the crank U has reached about forty-five degrees beyond the vertical position, the elliptic eccentric N drives the said valves y² and y³ forward to about the middle of their stroke, when the valve y² allows the steam to pass by the ways 3 and 4, on both sides of the piston of the inner cylinder, entirely filling this cylinder. The valve y³ also assuming the middle position, shuts both ways 7 and 8, which is to take place in due time, in order that the steam admitted by the valve y¹, and acting on the piston Z, may be prevented from entering into the chests C and D. The valve y², contrary to the ordinary mode of working, allows the steam to pass on both sides of the piston of the inner cylinder, in order that the steam may, at the required moment, keep this piston in proper equilibrium, and not impede its progress, it being required that this piston should recede by the effect of the other piston Z, whilst this latter is completing its stroke; consequently, if the small piston were not kept in perfect equilibrium, it would form resistance to the progress of the large one. This latter having now nearly completed its stroke, and the cranks V V having consequently passed for about thirty degrees beyond their dead-point, the small piston in its turn will have reached about the middle of its stroke, consequently with its crank U situated at about an angle of thirty degrees with its dead-point or 0°. At this moment the elliptic eccentric carries the valves y² and y³ at once from the middle to the end of their stroke, thereby opening the ways 3 and 7, the latter of which is in communication with the outer cylinder. The steam from the boiler, admitted by the pipes x and H¹, will now press on one side of the small piston, the steam existing in the cylinder on the other side of this piston taking its exit through the hollow part of the valve y², which latter sets the way 4 in communication with H, and enters into the chest C, the valve y³ of which allows the steam to pass by the way 7 into the outer cylinder, arriving in which, it finds the piston Z about completing its stroke, and ready for beginning its return stroke, at which moment this steam, a little compressed, viz, in the same manner as takes place in ordinary steam engines by what is called the lead of the valve, when this latter admits the steam a little before the piston begins its return stroke. It must be remarked here that in my improved arrangement this lead or advance does not take place by the effect of the valve y¹, but from the opposite side. This steam exerts its pressure on Z by its own elasticity, and also by being driven by the piston of the small cylinder, which piston is pressed on the opposite side by the steam admitted directly from the boiler. This piston G² of the small cylinder consequently drives the other, Z, till the steam is allowed to enter in B by the valves y¹ of the steam-chest D, which steam then compels the piston Z to complete its stroke in the same manner as in ordinary steam engines. In the meanwhile the valve y³ shuts the ways 7 and 8, whilst the valve y² admits the steam on both sides of the small piston, both valves taking the middle position by the effect of the elliptic eccentric N, each complete revolution of which consequently causes both valves y² and y³ to take three different positions.

The above-described motions taking place in regular succession to each other, the engine will be driven with the utmost regularity, and not the slightest variation in speed during each revolution will be perceptible in the cranks, for whilst those, V V, advance towards their dead-points, the other, U, is acting at full power, and *vice versa*. x¹ is the exit opening for the steam after having acted on the pistons.

The figs. 8 and 9 show a modification in the position of the slide valves, one of them, y¹, being set on one side of the outer cylinder, and the two others, y² and y³, close to each other on the opposite side of the said cylinder, for the purpose of rendering the engine more simple, and doing away with various connecting parts of the elliptic eccentric. In this modification the steam from the boiler is admitted in the steam-chest D', and

the same reaches the chest D by the way H¹, and passes into the chest C by the way H, and finally, by the way 3, the steam is admitted into the inner, and by that, 7, into the outer cylinder, in the manner as has been described above.

It will be readily understood that various modifications might be made in the respective positions of the steam-chests and of the valves, provided their principle of acting in respect to the cylinders be kept up. The same must be remarked about the cylinders, which, as has been said in the beginning of this specification, may be set concentrically to each other, or be situated side by side, viz, according to the principles illustrated in the figs. 10, 11, 12, and 13. In this latter arrangement the steam is admitted from the boiler by the tube x into the steam-chests D and D¹, and enters either into the small or into the large cylinder, according to which of the steam-ports is open at the time, viz, in the manner as has been described above in respect to the first arrangement. In fig. 10 of the drawing the passage 4 of the cylinder G being open, the steam from the boiler is admitted underneath the piston of this cylinder, whilst the steam from above this piston passes through the passages 3, H, and 6 underneath the large piston Z, which piston is compelled to pass its dead-point by the effect of the small piston. The steam arriving from the small cylinder underneath the piston Z, will act at this moment by expansion, in the manner as in an ordinary Woolf's steam engine. The small piston having thus driven the large one Z to forty-five degrees beyond its dead-point, the valves y³ shut the passages 6 and 5, and at the time the valve y², reaching the middle of its stroke, keeps open part of the passages 3 and 4, thus establishing the equilibrium of the steam on both sides of the small piston, which consequently will no longer offer any impediment to the progress of the large piston. The figs. 11, 12, and 13 show these positions of the valves. At the same time the equilibrium is thus established on the small piston, the valve y¹ opens the passage 8, and thereby admits the steam required for causing the large piston to complete its stroke. The large cylinder consequently receives at first a portion of the steam of the other cylinder, and afterwards the remainder directly from the boiler, which principle, in combination with that of admitting at the required moments steam on both sides of the small piston, in order to prevent this latter from offering any impediment to the progress of the large one, forms the conspicuous parts or main principles of my invention.

Having thus described and particularly ascertained the nature of my invention, and the manner in which the same may be put in operation, what I consider to be novel and original, and therefore claim as my invention in steam engines, is—

The arrangement of the steam-ports, passages, valves, and chests as described, with the pistons of two steam-cylinders and their connections, to act in combination with each other, for the purpose of mutually assisting each other for overcoming the dead-points of their strokes, when accomplished by the means substantially as described and illustrated in the drawings.

ERNESTO ANSALDI.
